UNITED STATES PATENT OFFICE

2,145,176

FLOCK CUTTING MACHINE

Andrew Hauge, Claremont, N. H., assignor to
 Claremont Waste Manufacturing Co., a corporation of New Hampshire

Application October 16, 1935, Serial No. 45,291

31 Claims. (Cl. 83—6)

My invention relates to flock cutting machines.

In the past machines of this character have usually comprised a rotary knife-carrying cylinder which cooperates with a knife-carrying concave or bed supported adjacent the cylinder and usually mounted below the same, as shown, for example, in the patents to Parent Nos. 1,688,296 and 1,688,297. A device of this character employing a single rotatable cylinder and concave possesses limitations in the matter of efficiency and output. It is contemplated by the present invention to employ a gang or series of such cutters so arranged that the unfinished or incompletely cut flock will be delivered from one cutter to the next in the series, while the finely cut flock will be withdrawn from each of the cutters in finished condition.

My invention has among its objects to provide an improved flock cutting machine which is of large capacity and of efficient operation. Other objects of my invention are to provide an improved flock cutting machine consisting of a series or gang of cutters and concaves arranged in sequence, whereby the unfinished material will be carried from one cutter to the next, and wherein the finely cut or finished material will be withdrawn from each cutter without being transferred to the next. A further object of the invention is to provide in a gang cutter of this character for the withdrawal from the last cutter of any material which may be unfinished or not sufficiently finely cut, and convey it again to the first cutter so that it will pass through the machine a second time. Other objects of the invention are to provide improved means for mounting and adjusting the stationary knives, to provide for efficient cooling of both stationary and rotating knives so as to reduce the temperature of the cooperating blades to enable continuous operation while preventing the flock from being heated to a point where it will be injured or catch on fire. Still further objects of the invention are the provision of means for controlling the fineness of the product and of handling the material expeditiously both in its introduction to the machine and its withdrawal therefrom after being delivered from the cutters. These and other objects and advantages of my improved construction will, however, hereinafter more fully appear.

In the accompanying drawings, I have shown for purposes of illustration, one embodiment which my invention may assume in practice.

In these drawings,—

Figure 1 is a side elevational view of a flock cutting machine embodying my invention;

Fig. 2 is an end elevational view of the machine;

Fig. 3 is a side view of the upper portion of the machine showing certain of the drive connections;

Fig. 4 is a sectional view on line 4—4 of Fig. 2, this view being somewhat enlarged;

Fig. 5 is a detail view of the feed conveyor;

Fig. 6 is an enlarged detail view showing the mounting of the stationary knives and associated parts;

Fig. 7 is a fragmentary detail view showing the arrangement for securing the sealing pipe between the knives;

Fig. 8 is a fragmentary plan view of a portion of one of the screens;

Fig. 9 is a detail view partly in section of one of the knife-holding lags;

Fig. 10 is a detail sectional view showing the manner of adjustably securing one of the knife lags to the side frames;

Fig. 11 is a sectional view on line 11—11 of Fig. 10, and

Fig. 12 is an elevational view of the knife-carrying cylinder shown partly in section to facilitate illustration.

The embodiment of my invention which I have selected to illustrate in the drawings comprises a pair of spaced side frames 1 supported in inclined position upon a base 2 by means of the upright standards 3. Brace members 4 and 5 extend from these standards to the side frames to hold them rigidly in place. Extending between the side frames are the knife-carrying cylinders or rotating cutters. These cutters are arranged in a series or a gang, and while the number employed may be varied within certain limits, five of such cutters, designated by the letters A, B, C, D and E, are shown in the drawings. Each of these cutters comprises a hollow cylinder 6 provided with radially projecting helically disposed lugs 7 to which the helical cutting knives 8 are removably secured. At the end of each of the cylinders are provided journals 9 and 10 by which the cylinders are rotatably supported in the side frames 1. It will, of course, be understood that there is one of such frames at each side of the machine to support each end of the cylinder. As shown more especially in Fig. 12, the knives are helically arranged upon the cylinder.

To provide for suitable cooling of the knives and cylinders, the latter are hollow, as shown at 11 in Fig. 4, and the cylinder journals are also hollow, as shown at 12 and 13 in Fig. 12. From

the passage 13 of each of the cylinders a pipe 14 extends to an auxiliary main pipe 15, which is connected to a water inlet pipe 16. From the other end of the cylinders branch pipes 17 extend 5 from the passage 13 to an auxiliary pipe 18 leading to a main water outlet pipe 19. It will be apparent that this will provide for a free and continuous flow of water through the cylinders to maintain the latter and the knives in a cool condition, providing for their continuous operation 10 without injury to the flock.

Cooperating with each of the rotating cutters is a concave or bed provided with cutting knives projecting radially toward the rotating cutter. 15 These stationary cutters or concaves are designated by the letters F, G, H, I and J, there being, of course, one for each of the rotary cutters. As they are all alike, a description of the construction of one will suffice for all. Each of these 20 stationary cutters comprises a group of hollow lags to which a knife is secured, these lags being adjustably mounted in the side frames so that they may be moved toward and from the rotating cutter. Each of these lags 20 comprises a 25 pair of angle members placed together to form a hollow body rectangular in cross-section extending from one side frame to the other, and a stationary knife 21 is secured to one side of each thereof. These angle members are welded together 30 at their meeting edges to form a watertight chamber so that cooling water may be introduced within the hollow lags, as will be hereinafter described. Spacing or reinforcing members, shown at 22 in Fig. 9, may extend between 35 the angle members to form a more rigid body, and to provide also for the passage through the lags of bolts 23 which secure the knives 21 thereon.

At each end these hollow lags are provided 40 with solid end members 24, and these end members are received between spaced parallel lugs 25 and 26 projecting inwardly from each of the side frames. It will be understood that there will be a pair of such lugs upon each of the side frames to receive the end of each of the lags 45 for the stationary knives. As shown in Fig. 10, the lags are securely fixed in position after they have been properly adjusted by means of a wedge 27 acting against a beveled surface of the lag end member 24. This wedge is forced into position by means of a screw 28 passed through one of the side frames 1 and provided with a lock nut 29 to hold it in place.

It will be understood that the lugs extend substantially radially toward the center of the cutting cylinder, and each lag is adjustable within these lugs to properly adjust the distance of the stationary knives from the cooperating rotary knives. For this purpose a cap piece 30 is 55 disposed across the upper edges of the lugs 25 and 26 and secured thereto by bolts 31. An adjusting screw 32 is rotatably mounted in this cap piece and threadedly engaged with the solid end member 24, whereby when the screw is rotated the end member of the lag will be adjusted 60 between the lugs. It will, of course, be understood that the screw 28 will be loosened to release the wedge when this adjustment is made. Keyed to the upper end of the adjusting screw 65 32 is an adjusting collar 33 by which the screw may be turned, the collar being held upon the screw by means of the nut 34. A thrust washer 35 is provided on the screw below the cap piece 30 to hold the screw against longitudinal movement. It will be apparent that the lags and 70

knives secured thereto may be radially and conveniently adjusted relative to one another, herein individually toward or away from the rotating cutter by this means to insure proper action upon the material.

Referring more especially to Fig. 4, it will be noted that the wall of one lag is slightly spaced from the wall of the adjacent lag, thus leaving a space through which the flock material might possibly escape. As the lags and their associated parts constitute the cover above each rotary cutter, it is necessary that these openings be closed. For this purpose a flange 36 extends from one of the lugs 26 to the adjacent lug 25, thus closing this space adjacent the side frames. 10 To close the remainder of the space, sealing pipes 37 are dropped therein, these sealing pipes contacting with the exterior wall of one lag and the knife on the adjacent lag and being of sufficient length to extend from the ends of the lugs on 15 one side frame to those upon the other to completely close the space above the rotary cutters. As each concave as herein illustrated comprises four of the hollow lags with associated knives, it is necessary to use three of such pipes. These 20 pipes may remain in place without the employment of any securing means therefor, but if found desirable, they may be secured by means of clips 38 secured to the pipes by bolts 39 and having extended ends 40 secured in the side 25 frames 1. Sheet metal covers 41 may be employed to close the space between the last lag of one cutter unit and the first lag of the next. It will be apparent that in this way a complete 30 cover will be formed over the cutters which extends between the side frames 1 and which will prevent the escape of the material.

Cooling water may be introduced into the hollow lags in a manner which will now be described. Extending into the upper portion of one end of 40 each of the lags is a flexible branch conduit 42, connected to an auxiliary main pipe 43, which in turn is connected by a branch 44 to the main water inlet pipe 16. At the other end of the lags branch conduits 45 are connected thereto, 45 which branch pipes are connected to an auxiliary pipe 46 joined by the pipe 47 to the main water outlet pipe 19. A constant flow of cooling water through the hollow lags to cool the lags and the knives secured thereto is thus assured, in such manner as to maintain the temperature 5 of the flock below the igniting point thereof.

An inclined elevator 48 carries the raw material from a hopper 49 to a point above the upper cutter unit, where it is delivered through a chute 50, shown more especially in Figs. 2 and 5, to the casing 51 of a screw conveyor 52 mounted above the upper cutting unit. This casing 51 is open at its lower portion, as shown at 53, to permit egress of the raw material to the first cutter throughout the length of the latter, and the casing is also provided with a deflecting plate 54 adjacent the end of the screw to deflect the material downwardly and cause it to be crowded into the zone of the rotating cutter A. This deflecting plate forces the material downwardly at the end of the screw flights with considerable pressure against the rotating cutter and the cooperating stationary knives.

A plate 55 extends from the conveyor housing 51 to the wall of the adjacent lag, and an apron 56 extends from the lower portion of the housing 51 below the rotary cutter A to form an enclosing housing for this cutter. Below the cutters B, C, D and E, a flock-receiving housing 57 is secured

to the side plates 1, and forms the lower housing for the main portion of the machine. Immediately below each of the rotary cutters is a concave screen 58 extending throughout the length of the cutter, each screen being provided with end flanges 59 by which it is secured to the side walls of the housing 57. Plates 60 which likewise extend throughout the length of the cutters, fill the spaces between these screens and between the apron 56 and housing 57. It may here be stated that the finely cut or finished material passes through the screens 58 into the receiver 57, and that the fineness of the product may be controlled by the fineness of the mesh of the screen employed.

It will be observed that all of the material treated by the rotary cutter A is transferred over the adjacent plates 60 to the rotary cutter B throughout the length of both cutters and the plate 60, there being no finished material withdrawn from the cutter A. When the material has been treated by the cutter B, that part which is of sufficient fineness will pass through the cooperating screen 58 into the receiver 57, while the remaining material which has not been sufficiently treated will be passed by the cutter B over the plate 60 to the next rotating cutter C. This will, of course, be repeated in the action of all of the rotating cutters in sequence. The material which is not of sufficient fineness to pass through the screen 58 of the lowermost cutter E will pass into a receiver 61. The inlet portion of a suction fan 62 is connected to this receiver by a pipe 63, and the coarse material in the receiver will be drawn therefrom by the fan and delivered through the pipe 64 to a separator 65 (Fig. 1) located above the hopper 49, the separator having a delivery outlet 66 discharging into the hopper, so that the coarse material will be returned by the elevator 48 to the rotary cutter A to pass through the machine again. From the separator a return pipe 67 leads to the side of the receiver 61 opposite that to which the pipe 63 is connected. The finished material collecting in the receiver 57 is withdrawn therefrom through an opening 68 by a suction fan 69 having a delivery pipe 70 to deliver the material wherever desired.

The moving parts of the machine are driven from a motor 71 by means of a belt 72 passing around a pulley 73, which is mounted on an extension of the journal 9 of the rotary cutter C, as herein illustrated. The cutter D is driven from the cutter C by means of the sprocket chain 55 74, and cutter E is likewise driven by the sprocket chain 75 from cutter D. Likewise, the rotating cutter B is driven from the cutter C by a sprocket chain 76, and a sprocket chain 77 extends from cutter B to cutter A to drive the latter. As shown in Figs. 1 and 2, a pulley 78 is mounted upon the journal of cutter A, and around this pulley is trained a belt 79 which drives a pulley 80 secured upon a shaft 81 rotatably mounted upon the standards 3. As shown in Figs. 2 and 3, the shaft 81 carries a sprocket wheel 82 from which sprocket chain 83 extends to a sprocket wheel 84 on a shaft 85, which carries the upper end of the conveyor or elevator 48. The shaft 86 of the screw conveyor 52 is driven by sprocket chain 87 from the shaft 85.

The suction fans 62 and 69 are driven by belts 88 and 89 trained about pulleys on the opposite ends of a shaft 90, which shaft is driven by belt 91 from a pulley 92 mounted upon the journal 75 of rotary cutter C.

A brief description of the operation of the device may now be appropriate. The raw material is fed to the hopper 49 and carried by the elevator 48 to the screw conveyor 52, from which it is forced forcibly downwardly by the plate 54 into the zone of the rotary cutter A and the cooperating stationary knives. The material is acted upon in this cutter unit and then passes downwardly over the adjacent plate 60 to the cutter B to be further comminuted. When it is treated by cutter B, that part which is of sufficient fineness will drop through the screen 58 into the receiver 57 to be withdrawn therefrom by the suction fan 69 and delivered wherever desired as finished material. The coarse material which does not pass through the screen 58 will pass downwardly over the plate 60 to the next rotary cutter, where the operation will be repeated. The coarse material which does not pass through the screen 58 of the lowermost cutter will be delivered into the receiver 61, where it will be picked up by the suction from the fan 62 and delivered to the separator 65, from which it will pass into the hopper for re-delivery to the machine.

As very little finished material could be obtained from the first rotary cutter A, it may be noted that an imperforate housing is provided beneath this cutter so that the entire charge of raw material passes from the first cutting unit to the second. As the material is cut by each of the succeeding units, however, the material which is of sufficient fineness to pass through the screens 58 is withdrawn and only the coarse material is delivered to the next succeeding cutting unit. Moreover, the fineness of the finished material may be regulated by the fineness of the mesh of the screens 58, as only the material passing through these screens is collected in the receiver 57. As the material passing through the successive cutting units is progressively decreased, the work demanded of these units is lessened and their efficiency increased, as they will only have to deal with that part of the material which has not passed through the screens.

As the cutting units are arranged upon an inclined plane, the material will pass from one to the other by gravity and by the windage induced by the cutters, so that no additional mechanism is required for this purpose. Attention is further directed to the fact that each of the cutters or cylinders delivers to the next throughout its full length in such manner as to give substantial capacity, while the screw conveyor above the first cutter similarly delivers throughout its length to the latter in such manner as to insure operation of the same at full capacity. By reason of the screw conveyor and its cooperating inclined plate, it will also be observed that a more even distribution of the material fed to the first cutter is obtained tending to compensate for any tendency of the spirally disposed knives on the cutter to carry material to one end of the cutter. Attention further is directed to the fact that not only do the cutters deliver to one another but that each cutter delivers from a portion of the same in an inclined plane above the portion 60 and the axes of the cutters to a corresponding portion of the next lower cutter. Further it is possible in my improved construction to utilize between the cutters a stationary directing means in the form of a plate 60, as distinguished from requiring any additional moving mechanism. These and other advantages of my improved construction will, however, be clearly apparent to those skilled in the art.

While I have in this application specifically described one form which my invention may assume in practice, it will be understood that this form is chosen for purposes of illustration and that the invention may be modified and embodied in various other forms without departing from its spirit or the scope of the appended claims.

What I claim as new and desire to secure by Letters Patent is:—

10. A flock cutting machine comprising a series of cutting units, each unit comprising a rotary cutter carrying a plurality of flock cutting knives and a plurality of stationary flock cutting knives cooperating therewith, and means for enabling the passage of coarse material by said rotary cutters laterally through successive units while separating out the finer material.
15. A flock cutting machine comprising a series of cutting units arranged in sequence along an inclined plane, each unit comprising a rotary cutter carrying a plurality of flock cutting knives and a plurality of stationary flock cutting knives cooperating therewith, stationary means for enabling the passage of coarse material by said rotary cutters laterally through successive units while separating out the finer material, and temperature controlling means associated with said rotary cutters and stationary knives for maintaining the flock below the igniting point during the operation of said units.
20. A flock cutting machine comprising a series of cutting units arranged in sequence along an inclined plane, each unit comprising a rotary cutter carrying a plurality of flock cutting knives and a plurality of stationary flock cutting knives distributed over and cooperating with an upper portion of said cutter, means within said rotary cutters for water cooling the knives thereof, an enclosing casing having means therein for water cooling said stationary knives, and means for withdrawing finely cut material from a bottom portion of certain of said units and directing the coarse material beneath the stationary knives of successive units.
25. A flock cutting machine comprising a series of cutting units disposed in sequence along an inclined plane, each comprising a rotary cutter carrying a plurality of flock cutting knives and a plurality of stationary flock cutting knives distributed over and cooperating with an upper portion of said cutter, and stationary enclosing means for said units having a bottom portion beneath each rotary cutter, means in said bottom portions of the second and following units for permitting withdrawal of the finely cut material therefrom, and lateral portions of the width of said rotary cutters receiving coarse material from one cutter and delivering it to the next and cooperating with said rotary cutters in passing coarse material through successive units.
30. A flock cutting machine comprising a series of cutting units comprising cooperating series of stationary and rotary flock cutting knives and arranged to act on the raw material in sequence, stationary means cooperating with said units for withdrawing the finely cut material from the more advanced of such units and passing the coarse material to successive units and discharging it from the last unit, and means for collecting and delivering the finely cut material while maintaining it separate from the discharged coarse material.
35. A flock cutting machine comprising a series of cutting units arranged in sequence along an inclined plane, each unit comprising a rotary cutter carrying a plurality of flock cutting knives and a plurality of stationary flock cutting knives distributed over and cooperating with an upper portion of said cutter, means within said rotary cutters for water cooling the knives thereof, an enclosing casing having means therein for water cooling said stationary knives, and means for withdrawing finely cut material from a bottom portion of certain of said units and directing the coarse material beneath the stationary knives of successive units.
40. A flock cutting machine comprising a series of cutting units disposed in sequence along an inclined plane, each comprising a rotary cutter carrying a plurality of flock cutting knives and a plurality of stationary flock cutting knives distributed over and cooperating with an upper portion of said cutter, and stationary enclosing means for said units having a bottom portion beneath each rotary cutter, means in said bottom portions of the second and following units for permitting withdrawal of the finely cut material therefrom, and lateral portions of the width of said rotary cutters receiving coarse material from one cutter and delivering it to the next and cooperating with said rotary cutters in passing coarse material through successive units.
45. A flock cutting machine comprising a series of cutting units disposed in sequence along an inclined plane, each comprising a rotary cutter carrying a plurality of flock cutting knives and a plurality of stationary flock cutting knives distributed over and cooperating with an upper portion of said cutter, and stationary enclosing means for said units having a bottom portion beneath each rotary cutter, means in said bottom portions of the second and following units for permitting withdrawal of the finely cut material therefrom, and lateral portions of the width of said rotary cutters receiving coarse material from one cutter and delivering it to the next and cooperating with said rotary cutters in passing coarse material through successive units.
50. A flock cutting machine having means for comminuting the raw material including a plurality of rotary cutters having top stationary knives and bottom screens, means for collecting the fine material passed through said screens, and means for receiving the coarse material laterally from beneath the stationary knives of one unit and directing it laterally beneath the stationary knives of the next unit.
55. A flock cutting machine comprising a series of cutting units, each comprising a rotary cutter, a screen lying generally below said cutter, and stationary knives positioned generally above said cutter, and means between certain of said units for delivering uncut material laterally from between the stationary knives and screen of one cutting unit laterally between the same elements of another unit.
60. A flock cutting machine comprising a series of cutting units, each comprising a rotary cutter, a screen lying generally below said cutter, and stationary knives positioned generally above said cutter, and means between certain of said units for delivering uncut material laterally from between the stationary knives and screen of one cutting unit laterally between the same elements of another unit.
65. A flock cutting machine comprising a series of cutting units, each comprising a rotary cutter, a screen lying generally below said cutter, and stationary knives positioned generally above said cutter, and means between certain of said units for delivering uncut material laterally from between the stationary knives and screen of one cutting unit laterally between the same elements of another unit.
70. A flock cutting machine comprising a series of cutting units, each comprising a rotary cutter, a screen lying generally below said cutter, and stationary knives positioned generally above said cutter, and means between certain of said units for delivering uncut material laterally from between the stationary knives and screen of one cutting unit laterally between the same elements of another unit.
75. A flock cutting machine comprising a series of cutting units, each comprising a rotary cutter, a screen lying generally below said cutter, and stationary knives positioned generally above said cutter, and means between certain of said units for delivering uncut material laterally from between the stationary knives and screen of one cutting unit laterally between the same elements of another unit.

- cutting unit laterally between the same elements of another unit, said last mentioned means including a stationary material directing element.
13. A flock cutting machine comprising a series of cutting units, each comprising a rotary cutter, a screen lying generally below said cutter, and stationary knives positioned generally above said cutter, and means between certain of said units for delivering uncut material laterally from between the stationary knives and screen of one cutting unit laterally between the same elements of another unit, said last mentioned means including a stationary material directing element extending substantially throughout the length of adjacent units.
14. A flock cutting machine comprising a plurality of cutting units arranged in sequence and each comprising cooperating rotatable and stationary flock cutting knives, means for delivering raw material to the first of said units, stationary means for directing the passage of said material laterally by said first unit to the next in sequence, and stationary means associated with the subsequent cutting units to withdraw the fine material therefrom and direct the passage of the coarser material laterally from said units.
15. A flock cutting machine comprising cutting means including stationary flock cutting knives and a rotating flock cutting cylinder delivering thereto, a hopper, and screw conveyor means extending laterally from beneath the hopper to deliver discrete raw material from said hopper to said cylinder, said screw conveyor means having a feed opening substantially coextensive with the length of said cylinder, and a screw delivering through said feed opening and extending substantially throughout the length of said opening.
16. A flock cutting machine comprising cutting means including a casing and a cylinder therein, and screw conveyor means to deliver raw material to said cylinder under pressure having a feed opening delivering thereto extending through said casing and substantially coextensive with the length of said cylinder, and a screw delivering through said feed opening and extending substantially throughout the length of said opening.
17. A flock cutting machine comprising cutting means including a casing and a cylinder therein having spirally disposed knives, power operated screw conveyor means to deliver raw material to said cylinder under pressure having a feed opening extending through said casing and substantially coextensive with the length of said cylinder, and a screw delivering said feed opening and extending substantially throughout the length of said opening, and outlet means through which material is projected by said cylinder and likewise extending substantially throughout the length of the latter.
18. A flock cutting machine comprising cutting means including a casing and a cylinder therein having spirally disposed knives, power operated screw conveyor means to deliver raw material to said cylinder having a feed opening extending through said casing and substantially coextensive with the length of said cylinder, and a screw delivering through said feed opening and extending substantially throughout the length of said opening, and outlet means through which material is projected by said cylinder and likewise extending substantially throughout the length of said cylinder, said cutting means also including stationary knife means cooperating with the knives on said cylinder and disposed between said delivery means and said outlet means.
19. A flock cutting machine comprising a rotary cutter, stationary knives cooperating therewith, and hollow lag members supporting said knives, said lag members each comprising a pair of angle members joined to form a hollow cooling fluid conducting body rectangular in cross-section and said knives engaging corresponding faces of said bodies.
20. A flock cutting machine comprising a rotary cutter and a stationary knife carrying structure cooperating therewith, said knife structure including a plurality of hollow lag members disposed longitudinally of said cutter and adjustably supported on said structure, knives supported upon and cooled by said lag members, and means for adjusting said lag members relative to each other and to their support to adjust said knives relative to said cutter.
21. A flock cutting machine comprising a rotary cutter and a stationary knife carrying structure cooperating therewith, said knife structure having individual hollow knife supporting and cooling lag members adjustably supported on said structure and disposed longitudinally of said cutter, a knife supported upon each of said lag members, means including flexible connections to said lag members for supplying a cooling fluid through said members, and means for adjusting said lag members relative to their support to adjust said knives relative to said rotary cutter.
22. A flock cutting machine comprising a stationary machine frame, a rotary cutter journaled therein, knife-supporting lag members supported on said frame, and knives secured to said members, said lag members being adjustably mounted on said frame and adjustable relative to each other and to their supports thereon toward and from the rotary cutter to adjust the distance of the stationary knives therefrom.
23. A flock cutting machine comprising a pair of side frame members, a rotary cutter journaled in said frame members, lag members adjustable relative to each other and extending longitudinally of the rotary cutter and having their ends adjustably mounted on said side frame members, and stationary knives carried by said lag members and adjustable therewith.
24. A flock cutting machine comprising a rotary cutter, a machine frame in which said cutter is journaled including a series of lag members supported adjacent said cutter and in part forming a housing therefor, stationary knives carried by said lag members to cooperate with the rotary cutter, and means on the opposite ends of said frame for adjusting said lag members relative to each other with the knives thereon toward and from the rotary cutter.
25. A flock cutting machine comprising a rotary cutter, a machine frame in which said cutter is journaled and having a series of lag members adjustably supported thereon adjacent said cutter and in part forming a housing therefor, stationary knives carried by said lag members to cooperate with the rotary cutter, and means at the opposite ends of said frame and adjustable relative to said lag members for adjusting said lag members relative to each other with the knives thereon toward and from the rotary cutter and holding the same in adjusted position.
26. A flock cutting machine comprising a cutting unit consisting of a hollow rotary cutter and stationary knives cooperating therewith, said knives being supported upon adjustable hollow lag members extending longitudinally of said cutter.

- means for passing cooling fluid through said rotary cutter and said lag members including adjustable connections to the latter, and means for adjusting said lag members relative to each other 5 to adjust said knives.
27. A flock cutting machine comprising a series of shearing units arranged one above the other in an inclined plane, each unit comprising a shearing cylinder and cooperating stationary shearing 10 knives on one side thereof and having on the other side thereof stationary screen means for separating the finer from the coarser material, substantially smooth imperforate inclined stationary means connecting said screen means for directing 15 the coarser material between said units, means for collecting the coarser material at the outlet end of the machine, and means connected to said collecting means to convey the coarser material again to the shearing units.
28. A flock cutting machine comprising a series 20 of shearing units arranged in sequence, a hopper from which raw material passes to the first of said units, a separator disposed above the hopper, stationary means for separating the coarse material 25 from the fine material and passing said coarser material through the machine, means for collecting said coarse material, air blast means for conveying said coarse material to the separator for re-delivery to the hopper, and an air blast return
- leading from said separator to the collecting means.
29. A flock cutting machine comprising a rotary cutter and a stationary knife structure co-operating therewith, said knife structure comprising hollow knife-supporting and cooling lag members extending longitudinally of said cutter and adjustable relative to each other and their supports and toward and from the rotary cutter, and means for passing a cooling fluid through said 10 lag members in different positions thereof.
30. A flock cutting machine comprising a rotary cutter, a screen lying generally below said cutter, stationary knives cooperating with said cutter and disposed generally above the latter, and 15 a plurality of hollow fluid cooling means carrying and cooling said stationary knives and adjustable individually to adjust said knives relative to said cutter.
31. A flock cutting machine comprising a rotary 20 cutter, a screen lying generally below said cutter, hollow lag members disposed generally above the cutter, stationary knives secured on said lag members to cooperate with the cutter, means for passing a cooling fluid through said lag members, and 25 means to adjust said lag members relative to each other to adjust the stationary knives with relation to the rotary cutter.

ANDREW HAUGE.
